UNITED STATES PATENT OFFICE

WILLIAM E. WESTON, OF KANSAS CITY, MISSOURI

HEATING AND DRYING APPARATUS

Application filed May 12, 1930. Serial No. 451,790.

My invention relates to heating apparatus and more particularly to furnaces or the like having fire boxes and flues for outlet of products of combustion in which gases move at relatively high speed, and through which a considerable amount of the heat units escape unused.

Heating apparatus of this general character may comprise a battery of boilers, each mounted in a fire box, and heated by coal supplied from a hopper or bin to the fire box, for example, the coal being automatically fed from a hopper to the fire box.

When the coal is stored in a bunker or bin exposed to weather it may receive and retain considerable moisture and the mass may be frozen whereby free flow of the coal toward the furnace is prevented, and a supply of coal provided in a bunker or hopper may contain sufficient moisture to seriously interfere with proper combustion. When the hopper delivers coal to a pulverizer from which the powdered coal is blown into a fire box, the moist condition of coal is still more objectionable, preventing free flow of the larger particles to the pulverizer and interfering with proper operation of the pulverizer and blower.

In view of the conditions above described and similar ones encountered in analogous situations, my invention has for its principal objects to employ the heat of products of combustion for supplemental heating after they have performed their normal service in a combustion chamber to heat a column of air by said products of combustion and conduct the heated air to an area to be heated, to employ the suctional effect of gases moving from a furnace through a flue for moving a column of air through a heating zone and a zone to be heated, to employ the heat of a furnace for heating and drying fuel, and to conduct air heated by a furnace into heating relation with a body of coal forming the fuel supply for the furnace.

In accomplishing these and other objects of my invention, I have provided improved details of structure, the preferred forms of which are illustrated in the accompanying drawing, wherein:

Fig. 1 is a vertical section of a furnace

including supports and a fuel supply conduit shown fragmentarily, and my improved air heating device combined therewith and shown fragmentarily.

Fig. 2 is a transverse vertical section of the furnace illustrating my improved device including an air conduit extending through the furnace and through a coal hopper into a smoke breeching of the furnace.

Referring in detail to the drawing:

1 and 2 designate front and back walls respectively and 3 and 4 the side walls forming the housing and support for batteries of boilers 5 and drums 6, the top of the housing being closed by a smoke run or breeching 7 connected to a flue 8 leading to a smoke stack (not shown) and having inlet openings 9 from the furnace.

10 designates a center wall of the housing forming separate fire boxes 11 and 12. The furnace is built on a floor 13 and each fire box has laterally spaced baffles 14 and 15 projecting vertically respectively, from the upper and lower portions of the furnace forming passes 16, 17 and 18, the products of combustion passing from the last pass into the openings of the smoke breeching and thence to the smoke stack.

The batteries of boilers are selected to represent one type of furnace to which the invention may be applied. Fuel may be supplied to the fire box through a conduit 19 communicating through a nozzle 20 with a pulverizer 21 that receives coal from the chute portion 22 of a hopper 23 located adjacent the furnace, the pulverized coal being blown through the conduit by a fan not shown, actuated by a motor 24 that also operates the pulverizing mechanism.

In order to heat the coal in the hopper for evaporating the moisture that may be carried thereby, I provide an air conduit 25 including a portion 26 extending laterally through the combustion chambers in the last passes thereof and adjacent the ports from the combustion chambers into the smoke breeching, but preferably beneath the drums, having an inlet 27 from atmosphere and including a portion 28 leading to the hopper, a portion 29 located in heating relation with

the hopper and a portion 30 leading from the hopper toward the flue.

The outlet end of the air conduit is fixed to the flue and preferably mounted in a suitable opening in the smoke breeching, and a nozzle 31 mounted on the outlet end of the conduit extends into the interior of the breeching and is curved in the direction of flow of products of combustion whereby the stream of gases passing from the fire boxes to the smoke stack will have suctional effect on gases in the conduit and draw air therethrough.

The portion 29 of the air conduit preferably comprises a plurality of pipe portions arranged for effective transmission of heat from the conduit to the hopper for heating the coal therein, and preferably comprises a grille-like assembly of pipes having headers 32 connected with adjacent ends of the conduit portions 28 and 30, the pipes preferably extending through the walls of the hopper into and through the hopper whereby coal introduced into the hopper will be partly supported by the grille and in contact with the grille portion of the conduit. The pipe portions are thus distributed to form an extended area of the conduit in heating relation with the hopper.

30 I further preferably install a nozzle 33 having an upwardly directed outlet 34 in the air conduit portion 30 whereby a pressure medium such as steam may be delivered to the conduit in the direction of desired flow of air for promoting flow of air into the inlet end of the conduit and through the conduit toward the stack.

An opening 35 is further formed in the conduit portion 28 between the furnace and the hopper, and a valve or damper 36 is pivotally mounted on the conduit to normally close the opening, whereby cold air may be admitted to the conduit to mingle with heated air moving from the furnace and temper the same.

In using the invention the air conduit may be located at any desired position in or adjacent a fire box or flue to receive heat therefrom and preferably is located adjacent the outlet from the fire box toward the flue to absorb from the products of combustion, heat that would otherwise be wasted into the flue.

55 The conduit is preferably fixed in openings provided therefor in the walls of the furnace and has one end open to atmosphere and portions leading to an area to be heated, the flow of air through the conduit being set up and continued by reason of the mounting of the 60 outlet end of the conduit in communication with the flue, whereby the draft created in the flue by operation of the furnace will accomplish circulation of air through the conduit, or by introducing a pressure medium into 65 the conduit.

The two means for setting up and maintaining flow of air through the conduit may be employed together and the supplemental steam inlet is preferably associated with a conduit having an outlet to the flue in order to assure circulation irrespective of extent of draft in the flue and for controlling the rate of movement of heated air through the conduit.

70 The conduit may be led to any area or chamber which it is desired to supply with heat, for example to a portion of a building or room, such as a greenhouse, dwelling, church or school room or the like, and the device is particularly useful for employing the otherwise wasted heat from a battery of boilers for heating purposes, and particularly for vaporizing moisture in coal contained in a hopper or bunker.

75 The heated air will effectually dry the coal and prevent solidification of lumps into masses either by adhesion due to moist condition or freezing, and thus assure free flow of coal from a bunker toward a hopper and from a hopper to a pulverizer.

80 Should air be passed at an undesirably high temperature into heating relation with a space to be heated, the damper 36 may be manipulated to admit more or less cold air to the conduit, for reducing the temperature of the column of air moving toward the flue, without suspending flow of said column, thus affording closer control of heat than would be possible by varying the amount of heated air that is permitted to move through the conduit, and preventing overheating of the heated space or of walls of the conduit located in heating relation with said space.

85 Attention is called to the fact that in the illustrated structure the outlet of the heated air conduit communicates with the smoke stack, chimney or breeching at a point higher than the space to be heated, in order to assure circulation of air through the conduit.

90 What I claim and desire to secure by Letters Patent is:

1. In combination with a furnace having a flue, and means including a fuel containing chamber member for supplying fuel to the furnace, an air conduit located to receive heat from the furnace and having a portion located to transmit heat to said chamber member and an outlet end extending into the flue.

115 2. In combination with a furnace having an outlet for products of combustion moving from the furnace, and a chamber member, a conduit located to receive heat from the furnace and having a portion extending through said chamber and inlet and outlet ends communicating respectively with atmosphere and with said furnace outlet for supplying air to and creating suction in said conduit.

125 3. In combination with a furnace having a flue, means including a fuel containing reser-

voir for supplying fuel to the furnace, and a conduit located in heat-receiving relation with the furnace and having a portion located in heating relation with fuel in said reservoir and an outlet end extending into said flue.

4. In combination with a furnace having a flue and a bin for containing coal adapted to be fed to the furnace, a conduit having an air inlet from atmosphere extending through the furnace and having a plurality of portions extending through said bin and an outlet end extending into said flue.

5. In combination with a furnace having a flue and a bin for containing coal adapted to be fed to the furnace, a conduit having an inlet from atmosphere extending through the furnace and having a plurality of portions extending in said bin and an outlet end extending into said flue, and means including a nozzle projecting into said conduit for delivering a pressure medium thereto.

6. Heating and drying apparatus including in combination with a furnace having a flue, and a chamber member, a conduit having an inlet end open to atmosphere, a portion in heat exchanging relation with the furnace, an intermediate portion for exchanging heat with the chamber member, and an outlet end portion connected with the flue for inducing flow of air into the conduit responsively to draft in the flue.

In testimony whereof I affix my signature.
WILLIAM E. WESTON.
